UNITED STATES PATENT OFFICE.

WILLIAM A. BEINKE, OF WEBSTER, IOWA.

AUTOMATIC CUT-OFF.

1,179,270.

Specification of Letters Patent. Patented Apr. 11, 1916.

Application filed December 4, 1915. Serial No. 65,100.

To all whom it may concern:

Be it known that I, WILLIAM A. BEINKE, a citizen of the United States, residing at Webster, in the county of Keokuk and State 5 of Iowa, have invented new and useful Improvements in Automatic Cut-Offs, of which the following is a specification.

This invention is an improved automatic cut off for use on rain water conductor pipes 10 for carrying rain from a roof and storing the same in a cistern, tank, or the like, the object of the invention being to provide an improved device of this character which automatically causes the rain water to be discharged 15 upon the ground until the roof has been thoroughly rinsed and then changes the course of the water and causes it to be discharged into a reservoir, cistern, or the like and thus prevents dust or dirt from being 20 discharged into the cistern with the rain water.

The invention consists in the features of construction, combination, and arrangement of parts, hereinafter fully described and 25 claimed, reference being had to the accompanying drawings, in which:

Figure 1 is a side elevation of an automatic cut off constructed in accordance with my invention. Fig. 2 is a vertical sectional 30 view of the same. Fig. 3 is a detail sectional view of the same on the plane indicated by the line $a-a$ of Fig. 2.

In the embodiment of my invention, I provide a vertical tube 1 which is connected 35 to a down spout 2 and is arranged to discharge into a cistern or other suitable reservoir such as indicated at 3, and I also provide a tubular waste spout or arm 4 which extends from one side of the tube 1 and is 40 arranged in an inclined position. The tube 1 and the waste discharge arm 4 thereof are each here shown as rectangular in cross section. A cut off valve 5 is provided which is arranged in the member 1 and is provided at 45 its lower side with a pivoting shaft 6 which is mounted in bearings in opposite sides of the member 1 and the said cut off valve is adapted to be turned to a vertical position to close across the inner end of the waste arm 4 50 and cut off communication between the member 1 and the member 4 and the said valve is also adapted to be arranged in an inclined position across the member 1 so as to open the inner end of the member 4 and 55 establish communication between the said

members. A lever arm 7 is attached to one end of the pivoting shaft 6 and a bucket or other suitable receptacle 8 is suspended from said lever arm as at 9. A coiled retractile spring 10 has its upper end attached 60 to an ear 11 on one side of the member 1 and its lower end attached to the lever arm 7 as at 12, the said spring serving to normally close the valve in the member 1 and hence open the inner end of the member 2 65 and establish communication between said members so that the first rain which falls upon the roof will be deflected by the valve from the member 1 into the member 4 and hence discharged upon the ground and prevented from entering the cistern or reservoir. 70

A discharge spout 13 of reduced capacity leads downwardly from the member 4 and is arranged at one side thereof and is adapted 75 to discharge into the bucket or other receptacle suspended from the lever arm.

A controlling valve 14 is pivotally mounted as at 15 in the arm or member 4 and may be arranged at any desired angle in said arm 80 or member to deflect any desired proportion of the water passing through the member 4 to the spout 13 and hence to the bucket. This controlling valve may be secured in any desired adjusted position by means of a 85 screw 16 which extends upwardly from its free end and operates in a curved slot 17 in the upper side of the arm 4, said screw being provided with a clamping nut 18. Hence, the bucket may be filled with rain 90 water rapidly or slowly as may be desired and according to the superficial area of the roof. When the bucket becomes filled with water, its weight overcomes the tension of the spring and causes the lever to move the 95 valve 5 to a vertical position in the tubular member 1 thus causing said valve to cut off communication between the members 1 and 4 so that the rain water thereafter passes directly into the cistern or reservoir. 100

It is believed that from the foregoing description the nature and advantages of the invention will be readily apparent without requiring a more extended explanation and therefore the same has been omitted. However, I desire to have it understood that various changes in the construction, and arrangement of the parts may be resorted to when desired as fall within the scope of the appended claims. 105

Having described the invention, what is claimed is:

1. The herein described automatic cut-off comprising a pipe for connection to a down spout and to discharge into a cistern or the like, a waste pipe at an angle to and leading from the first named pipe, a cut off valve in the first-named pipe to cut off or establish communication between the same and the waste pipe, a spring to normally close said valve across the main pipe, a lever connected to said valve to operate the same, a vessel suspended from said lever, a spout connected to the bottom of the waste pipe, near one side thereof and arranged to discharge into the vessel, a controlling valve in said waste pipe pivotally connected thereto at the same side thereof as the spout and movable toward and from said side to control the quantity of water discharged into the vessel by said spout.
2. The herein described automatic cut-off comprising a pipe for connection to a down spout and to discharge into a cistern or the like, a waste pipe at an angle to and leading

from the first-named pipe, a cut-off valve in the first named pipe to cut off or establish communication between the same and the waste pipe, a spring to normally close said valve across the main pipe, a lever connected to said valve to operate the same, a vessel suspended from said lever, a spout connected to the bottom of the waste pipe, near one side thereof and arranged to discharge into the vessel, a controlling valve in said waste pipe pivotally connected thereto at the same side thereof as the spout and movable toward and from said side to control the quantity of water discharged into the vessel by said spout, the said waste pipe having a curved slot in its upper side and said controlling valve having an adjusting screw arranged for movement in said slot. 30 35 40

In testimony whereof I affix my signature in presence of two witnesses.

WILLIAM A. BEINKE.
